UNITED STATES PATENT OFFICE.

CLARENCE M. FROST, OF ATTLEBORO, MASSACHUSETTS.

AERATED WATER-SUPPLY DEVICE.

1,391,311.

Specification of Letters Patent. Patented Sept. 20, 1921.

Application filed February 7, 1920. Serial No. 357,001.

To all whom it may concern:

Be it known that I, CLARENCE M. FROST, a citizen of the United States, residing at Attleboro, in the county of Bristol and State of Massachusetts, have invented certain new and useful Improvements in Aerated Water-Supply Devices, of which the following is a specification, reference being had therein to the accompanying drawing.

10 This invention relates to means for supplying moistened air to the fuel-intake of an internal-combustion engine.

It is an object of the invention to provide a device of that kind that will furnish air and water in proper regulated quantities and in proper proportions to a combustible charge in an engine-intake after it has been delivered thereto from a carbureter or the like.

20 By the use of such a device carbon deposits in an engine and the improper functioning resulting therefrom are eliminated entirely or materially reduced, consumption of fuel is reduced, more power is obtained from the engine with a given amount of fuel, and generally a more economical, efficient, and satisfactory operation of the engine is obtained.

When read in connection with the description herein, the details of construction, arrangement of parts, and installation of the device will be apparent from the accompanying drawings, forming part hereof, wherein an embodiment of the invention, adapted to be associated with a motor-vehicle, is disclosed, for purposes of illustration.

30 While the disclosures herein exemplify what now is considered to be a preferable embodiment of the invention, it is to be understood that it is not the intention to be limited necessarily thereto in interpretation of the claims, as modifications and adaptations within the limits of the claims can be made without departing from the characteristics of the invention.

45 Like reference-characters refer to corresponding parts in the views of the drawings, of which—

Figure 1 is a view of the device installed in a motor-vehicle;

50 Fig. 2 is a vertical sectional view of the water-container;

Fig. 3 is a top view thereof, the cover being omitted;

Fig. 4 is a bottom view of the cover;

55 Fig. 5 is a sectional view of the control valve;

Fig. 6 is a view of the member for operating that valve and of the graduated dial associated therewith; and

Fig. 7 is a view of the nozzle.

Having more particular reference to the drawings, A designates a pipe leading from a carbureter B to a manifold C of an internal-combustion engine D of a vehicle, E an upright partition or wall to the rear of the engine, and F the instrument-board of the vehicle.

A water-container 8, having a drain-valve 9 and a side opening closed by a sight-plate 10, is secured by lugs 11 to the partition E.

The upper wall of the container has a centrally-positioned comparatively large depression affording a chamber 12, which is closed by a substantially dome-shaped circular cover 13.

The cover has a central vertical threaded opening, which holds an exteriorly-threaded hollow outlet member or coupling 14. By turning in its threads the coupling may be made to extend more or less below the cover, and its lower end 15 is burred to substantially bell shape. A lock-nut 16 holds the coupling against displacement from adjusted position.

Machine-screws 17 hold the cover, in fluid-tight association with the upper wall, against a gasket 18 in an annular seat 19 of that wall.

The lower wall of the chamber 12 is a circular diaphragm or partition 20, which constitutes an integral portion of the upper wall of the container. It is concave on its lower side and convex on its upper, and thus it is upwardly curved or substantially dome shape, it generally corresponds to the contour of the cover, and it is concentric therewith. A series of equally-spaced cutter-holes 21, arranged in a circle concentric with the diaphragm, extend substantially vertically therethrough from the interior of the container to the chamber 12, and several overflow-holes 22, equally spaced at the periphery of the diaphragm, extend between the chamber and the interior of the container.

At one side of the chamber 12, the upper wall of the container has an intake-depression 23, from which extends inside of the container an air-intake tube 24. This tube is disposed substantially in a semi-circle, and its free end is open and spaced from and directly below the center of the diaphragm 20.

A similar intake-depression 25 is at another side of the chamber in the upper wall, and preferably diametrically opposite to depression 23. A tube 26 extends into the 5 container from depression 25, in its lower portion it is disposed substantially horizontally above the bottom of the container, in that portion it has a plurality of cutter-holes 27 opening through its upper side, and 10 it is closed at its inner end.

A tube or pipe 28 is connected with the coupling 14 and affords communication between the chamber 12 and a coupling member 29. That coupling member contains a 15 port controlled by a needle-valve stem 30, which is operable by a finger-piece 31 over a graduated dial 32 on the instrument-board F.

Another tube or pipe 33 is connected with 20 the coupling member 29 and is arranged to receive fluid from the valve-controlled port. It leads therefrom to a spray-nozzle 34 extending into the pipe B that conveys formed charges from the carbureter to the manifold. 25

Enough water is supplied to the container to bring its level just below the inner end of the air-tube 24 by pouring into the depression 25, whence it passes through 30 the immersed tube 26 and out of the holes 27. In introducing water into the container, care should be exercised to avoid exceeding the maximum water level indicated by the line W in Fig. 2. Ordinarily the container will have a water capacity for 100 miles of travel under operation of the motor-vehicle engine with which it is associated.

In operation, the fuel-inspirating action 40 of the engine will create a partial vacuum in the pipes 33 and 28 and in the container. This results in flow of air through the tube 24 into the container. The ratio of the capacity of that tube to the combined area of 45 the holes 27 of the tube 26 is such that air also will be drawn in through that tube and out of those holes, whence it will percolate through the water and reach the air-space thereabove in a moistened state. This moistened air is caught by and becomes mingled with the air emitted from the tube 24, and the mixture of air and water strikes the diaphragm 20 and the elements thereof become more intimately commingled.

50 Moisture-laden air is drawn into the chamber 12 through the holes 21 and thence into the pipe 28. Free and excess water that may be in the chamber will drain out through the holes 22.

60 By reason of its dome shape or inclination from the center toward the periphery, resulting in the drainage of free or excess water from the central portion, the latter portion of the diaphragm has less moisture 65 over it than its surface nearer the periphery,

and the central portion, therefore, is termed a "dry-mound."

Accordingly, the nearer the bell-shaped entrance 15 of the coupling 14 is to the dry mound, the less water is drawn into the pipe 70 28. Thus the proportion of water in the air drawn from the chamber may be regulated by turning the coupling and the entrance toward or from the dry mound. Ordinarily, a mixture of about 100 parts of air to 75 one part of water is required.

Air and water thus associated pass through the pipes 28 and 33 to the nozzle 34, by which the mixture is sprayed in vaporized form into and thoroughly mixed 80 with the fuel-charge in the pipe leading from the carbureter to the manifold. The amount of the mixture may be regulated by the valve 30, the dial 32 being graduated to show the quantity supplied at the different 85 positions of the finger-piece 31.

The vaporized water passing into association with the fuel-charge formed by the carbureter results in better combustion in the engine-cylinders through the action of 90 its oxygen and hydrogen, much of the carbon that otherwise would be deposited on the cylinder-walls is consumed, most of that unconsumed is blown out with the exhaust, and such of it as may remain is not in a 95 form to incrust in the cylinders.

Moreover, as a result of the introduction 100 of vaporized aerated water into the charge, the feed-pipe and engine-block are full of vaporized fluids at all times, so that the instant the intake-valve of a cylinder opens the cylinder fills at once to its capacity; when the valve closes and the piston compresses and the charge is fired, increased power is derived from combustion of a fully 105 vaporized fuel under extreme pressure; and the gases from the water permeate and loosen carbon that may have been deposited in the cylinder.

Having thus described my invention, 110 what I claim as new, and desire to secure by Letters Patent, is—

1. A device for supplying aerated water to an internal-combustion engine comprising a water-container having a chamber in its upper portion, a perforated partition between said chamber and the lower portion of the container, a tube arranged to discharge air above the water level upwardly against said partition, another tube arranged to discharge air into water in the container, and an outlet member from said chamber arranged to be connected with an engine. 115 120 125

2. A device for supplying aerated water to an internal-combustion engine comprising a water-container having a chamber in its upper portion, a dome-shaped partition between said chamber and the lower portion of the container having an imperforate cen- 130

- tral portion and openings at other places, an outlet member for said chamber positioned above and adjustable toward and from the central portion of said partition, 5 a tube arranged to discharge air above the water level upwardly against the central portion of said partition, and another tube arranged to discharge air into water in the container.
- 10 3. A device for supplying aerated water to an internal-combustion engine comprising a water-container having a chamber in its upper portion, a dome-shaped cover for said chamber, a dome-shaped partition be- 15 tween said chamber and the lower portion of the container having an imperforate central portion and openings at other places, an outlet member in said cover adjustable toward and from the central portion of said 20 partition, a tube arranged to discharge air above the water level upwardly against the central portion of said partition, and another tube arranged to discharge air into water in the container.
- 25 4. A device for supplying aerated water to an internal-combustion engine, comprising a water-container having in its upper wall a depression containing a chamber and having also intake-depressions, a cover over 30 said chamber, a perforated partition be- 35 tween said chamber and the lower portion of the container, a tube leading from one of said intake-depressions arranged to discharge air above the water level and below said partition, a tube leading from another 40 of said intake-depressions arranged to discharge air into water in the container, and an outlet member for said chamber.
5. A device for supplying aerated water to an internal-combustion engine, comprising a water-container having in its upper wall a depression containing a chamber and having also intake-depressions, a dome-shaped cover over said chamber, a dome-shaped partition between said chamber and the lower portion of the container having 45 passages therethrough, an outlet member in said cover adjustable toward and from said partition, a tube leading from one of said intake-depressions arranged to discharge air above the water level and below said partition, and a tube leading from another of said intake-depressions arranged to discharge air into water in the container.

In testimony whereof I affix my signature. 55
CLARENCE M. FROST.
